UNITED STATES PATENT OFFICE.

ALEXANDER LOGIN LINEFF, OF CHISWICK, COUNTY OF MIDDLESEX, ENGLAND.

MEANS FOR SUPPLYING ELECTRICITY TO TRAM-CARS.

SPECIFICATION forming part of Letters Patent No. 423,874, dated March 18, 1890.

Application filed August 27, 1889. Serial No. 322,099. (No model.) Patented in England July 11, 1888, No. 10,092.

To all whom it may concern:

Be it known that I, ALEXANDER LOGIN LINEFF, of 88 High Road, Chiswick, in the county of Middlesex, England, have invented certain new and useful Improvements in Means for Supplying Electricity to Tram-Cars or other Vehicles, (for which I have obtained Letters Patent in England, No. 10,092, dated July 11, 1888,) of which the following is a specification.

My invention has reference to supplying electricity to tram-cars and other vehicles by means of electrical conductors laid throughout the line along which the vehicles have to travel; and its objects are to secure convenience of arrangement and efficient electrical contact between the car and the electric conductor or main.

In the accompanying drawings, Figure 1 shows in cross-section a portion of a track with one form of conductor and a pair of surface magnetic pieces. Fig. 2 is a side elevation of a portion of the same, on a smaller scale, showing the arrangement of the magnet. Fig. 3 is a plan view with the magnet in place, and Fig. 4 an end view of the same, partly in section. Figs. 5 and 6 show in side elevation and cross-section a modification in the arrangement of the track, and Fig. 7 shows in detail a rolling pole-piece. Figs. 8 and 9 show in side elevation and plan view means for carrying the magnet from the car. Figs. 10, 11, and 12 are cross-sections showing other modifications in the arrangement of the road. Figs. 10^a and 12^a show in cross-section and side view the construction and arrangement of the electrical and magnetic mains of Figs. 10 and 12, drawn full size. Figs. 13 and 14 are plan views of two modes of laying the surface-pieces, and Figs. 15 and 16 show in side elevation and cross-section the magnet with rotating pole-piece.

The portion of the tracks shown in the figures is only so much as relates to my invention, the running-rails, (except in Figs. 6 and 12) not being shown.

The characteristic feature of my invention is the use, for traction purposes, of a magnetic circuit composed of (a) a magnet attached to the car or vehicle, (b) surface magnetic pieces electrically and magnetically in-

sulated from each other, and (c) a continuous magnetic conductor forming a component part of the main electric conductor conveying the working-current. In this magnetic circuit the only portion which moves along with the car or vehicle is (a,) the magnet itself. Of the remaining parts of the circuit one (b) is a fixture, and the other (c) has only a slight upward motion, for the sole purpose of producing the electric contact, and which, after the magnetic influence is over, returns to its normal position by the force of gravity. The closing of the magnetic circuit causes a continuous and flexible magnetic component of the sealed electrical conductor to come in contact with the surface magnetic pieces, and thus temporarily charge them with the electric current, which is collected by suitable means and conveyed to apparatus for converting the energy of the current into mechanical energy for traction or for other purposes. The position of the magnetic circuit is continually changing as the car or vehicle moves along, and fresh portions of the continuous flexible magnetic component of the conductor (hereinafter called the "magnetic main") are continually being drawn into the magnetic circuit, and thus other surface magnetic pieces (immediately under the car or vehicle) become in turn the medium for conveying the electric current from the conductor to the converting apparatus. The magnetic circuit is in fact the only means of "tapping" the current at any desired part of the conductor, as the latter is entirely sealed from the surface, and no purely mechanical means will avail for this purpose.

The arrangement of the various parts forming the conductor may vary in detail according to the position it occupies with regard to the running-rails, so long as the principle involved is the same—viz., to produce a magnetic circuit, part of which is formed by means of a continuous magnetic main.

Referring now to Figs. 1, 2, and 3, M M' are the surface magnetic pieces, which in this instance consist of rails in short lengths, about three feet long, placed parallel, and magnetically insulated both longitudinally and transversely. The electric insulation is only longitudinal, the two parallel opposite lengths

of rails being electrically connected in pairs, but every pair is electrically insulated from the adjacent pairs. The connection is made by means of bolts B B and distance-pieces D, 5 of some non-magnetic, but electricity-conducting, material, as brass, copper, &c. The two rails are set a short distance apart to form a groove to guide the pole-pieces of the electric magnet. The lower inner flanges *m m'* 10 of the rails M M' are at a considerable distance from each other, in order to prevent magnetic leakage, and for the same purpose the ends of each length of rail are, by preference, beveled off, as shown in Fig. 2.

15 At a short distance below the lower surface of the rails M M' lies the magnetic main, which consists of a continuous, flat strip of iron F, which rests upon a bare copper conductor or electrical main C. The rails and 20 conductors are inclosed in a trough A, and surrounded with asphalt or any other suitable insulating composition, which thus forms a closed channel under the rails, and the trough is let into the roadway. The magnetic main F is intended to rise and touch 25 the flanges *m m'* under the influence of the passing magnet. To prevent oxidation and reduce the contact resistance, both the magnetic main and the bottom part of the magnetic rails might be galvanized, tinned, &c. 30 The electric conductor C may be made in lengths about equal to the length of the troughs, and when the troughs are laid in position the separate lengths of conductor will 35 be joined in any suitable and convenient manner—as, for instance, by means of flat strips or keys which enter both ends of a conductor length. Pins *f*, of some non-magnetic material, may be provided at certain distances apart on the conductor, which pins 40 project through holes in the strip F and prevent any lateral movement thereof.

N and S, Fig. 1, represent the pole-pieces of the magnet, and they are so arranged that 45 the pole-piece N travels in front over the magnetic rail M, while the pole-piece S moves over the rail M' at a distance of not less than the length of one piece of the magnetic rail from the pole-piece N. In some cases I may 50 find it desirable to have only one magnetic rail projecting on the surface of the road, as one rail will be sufficient to convey the magnetism and to collect the current, the other rail, which may consist practically of angle- 55 iron, being buried in the insulating compound surrounding the magnetic rails. I call such a hidden magnetic rail a "blind" rail. Three arrangements on this plan are clearly shown in Figs. 10, 10^a, 11, 12, and 12^a.

60 M is the active or exposed magnetic rail, and M' the blind rail.

E represents a hard insulating material forming a support for the asphalt or similar material in which the rails are embedded.

65 G is an earthenware support containing the conductor C, with its magnetic component

F. At the same time the support G may serve as a bed-plate for the magnetic rails to lie on. *a a* are grooves to facilitate the draining away of any water that may have accidentally found its way into the channel. After the earthenware slabs, with the conductor and the magnetic rails, have been placed in the trough the whole is filled with asphalt or similar material.

75

The same letters in the above figures denote corresponding parts in other figures representing the conductor.

As previously stated, the channel under the magnetic rails is sealed water-tight from the 80 surface of the road. As it is, however, important to get rid of any water that may accidentally find its way into the channel through cracks in the bituminous composition or otherwise, the channel is provided at 85 certain distances apart, and especially at the lowest portion of the road, with drain-pipes or branches of any convenient description, communicating with the main sewer and cut off from it by means of suitable siphon-traps. 90 Moreover, to expel any damp or moisture from the channel, a current of dry air can be circulated in the channel by means of fans worked by small electrical motors placed under the pavement at suitable distances apart. 95

The air, previously dried by any well-known means, is forced by the fan or pump into the channel, and is allowed to escape at suitable places provided, by preference, under the pavement. The general principle of the 100 above is so simple that it needs no illustration. When the poles of the "picking-up" magnet are caused to act on one line of magnetic rails only, the two poles must face or touch, as the case may be, two separate pieces 105 or lengths of rail in order to force the magnetic lines through the magnetic main. The action of the magnet will also be considerably increased if the opposite lengths of rails are placed on the hit-and-miss principle. 110

Fig. 13 shows this arrangement for exposed double magnetic rails. The breaks between the separate lengths of one line of magnetic rails M' M' M³ are just opposite the center of the corresponding lengths of the other line, 115 and the electrical connection, by means of bolts B B, is made as shown in the figure. By this arrangement, however, the length of that portion of the rails that is electrically charged is increased by half, or at times by 120 a whole length, and consequently the extent of surface from which leakage may take place is increased. It also leaves a certain portion of the rail unconnected with the corresponding opposite length, and the projecting part 125 is supported exclusively by the bituminous compound surrounding it. To obviate these difficulties, I prefer to use what I may term a "partial hit-and-miss arrangement," as shown in Fig. 14. In this case the distance between 130 the extremities of the rails M and M' is only a small fraction of the length of a piece of

the magnetic rail. This arrangement is shown as applied to single exposed magnetic rails, the upper part in the drawings representing the blind rail, the lower the active rail.

5 The magnet P, which may be of any suitable kind, is fitted to a separate carriage, which can be attached to the car or vehicle in any suitable manner. In the present instance the magnet is an electro-magnet, the core of which is wound with fine wire H and works in shunt with the main current.

N and S are the pole-pieces, as before mentioned, and I and I' collecting and guiding wheels made of some non-magnetic metal and 15 with flanges which run in the groove between the rails M M'.

F is the magnetic main, which is shown in Fig. 2 as attracted under the influence of the pole-pieces to the under side of the rails M 20 M'. The magnetic rails are thus put into electrical communication with the main conductor C, and the current passes from the rails through the wheels I I' partly to the bobbin H and partly to the motor on the vehicle, and 25 thence by the return-conductor (running rails) to the generating-station. As the vehicle advances the magnet keeps picking up fresh portions of the magnetic main F, and consequently puts in electrical communication 30 fresh portions or lengths of the magnetic rails.

Instead of fitting the collecting apparatus to a separate carriage secured to the car, the magnet may be fixed to a frame carried by 35 the car, as shown in Figs. 8 and 9. Here N and S are the poles and H the bobbin of the magnet, which is suspended from the frame U. This frame has its ends V and V' rounded and is so mounted on the angle-irons W and 40 W' as to be free to move laterally along them. The angle-irons W W' are fixed to the cross-pieces X X, forming part of a frame-work carried by the axle-boxes of the car or vehicle. The frame U, and with it the magnet, is therefore 45 free to move in a lateral direction parallel to the angle-irons W W', and as the ends of the frame U are rounded it is also capable of a slight axial motion about its center. The magnet is by this arrangement enabled 50 to maintain its proper position directly over the magnetic rails on curves and in spite of small transverse motions of the wheels.

In some cases, when the picking-up magnet is not provided with a separate carriage, means for retaining the magnet in its proper 55 position over the magnetic rails and for collecting the current from them are necessary. To retain the magnet in position, I employ 60 guide-pieces t t', Fig. 8, attached to the pole-pieces. These guides, which are preferably made of non-magnetic metal, slide in the groove between the magnetic rails, and they also serve the purpose of keeping the groove clear of dirt. The current may in this case 65 be collected by the brushes b b, Fig. 8, of some non-magnetic material, which sweep along

the surface of the magnetic rails. The pole-pieces and collecting-wheels may also be combined, as shown in Fig. 7, which represents longitudinal and transverse sections 70 of a rolling pole-piece. The core of the magnet P terminates in a portion of a hollow drum of cast-iron, made in two pieces for the convenience of fitting. The drum in this case is not only a device to connect mechanically and magnetically the core with the rolling pole-piece proper, but helps at the same time, by means of projections N and N', to direct and concentrate the magnetic lines, and thus helps the rolling pole-pieces proper. 80 In fact this arrangement might be considered as a pole-piece shown in Figs. 2, 3, and 4, with an iron wheel inside, intended both to convey the magnetic lines and to collect the current from the magnetic rails. On an iron 85 spindle L is mounted a wheel I', provided with a flange R in the middle of the rim, which runs in the groove between the magnetic rails. The flange and the portion of the rim which lies to one side of it and is 90 marked T, is made of some non-magnetic metal, such as brass. The rest of the wheel is of iron. The iron portion of the wheel I' runs on the rail M, and it will be seen that though both magnetic rails M and M' are in 95 electrical contact with the wheel its direct magnetic influence is confined to M; with which alone it has magnetic contact. A similar wheel at the other end of the magnet, and forming its opposite pole, will be in magnetic 100 contact with M' only, so that the magnetic rails become poles of opposite polarity. When only one magnetic rail appears on the surface, the rolling pole is simply an iron 105 wheel without any flanges, and the face of the wheel is slightly narrower than the magnetic rail, so as to allow a certain margin for lateral motion of the car. As there is no guide for the wheel, the magnet must be fixed to the car in such a manner that the latter 110 will guide it over the rail and yet be capable of some slight vertical motion to compensate for the slight unevenness of the magnetic rails as compared with the rolling-rails. The arrangement is shown in Fig. 15 as adapted 115 to a side magnetic rail, as described and illustrated in Fig. 12, Fig. 15 being an elevation of the magnet, showing the method of attaching it to the vehicle, and Fig. 16 is a section through the center of one of the rolling pole-pieces. H is the bobbin, P P' the 120 pole-pieces, each of which consists of a wheel I, incased in a hollow drum provided with the projecting pieces N N' S S', for the purpose of directing and concentrating the magnetic lines. The pole-pieces are provided with pins p p, made of a non-magnetic material. These pins slide in sockets in the bar K, which is secured to the angle-irons x x, which themselves are attached to the frame 125 carried by the axle-boxes of the vehicle. The magnet, owing to the sliding of the pins in

the sockets, is capable of a small vertical motion with respect to the car.

In order to obviate the inconvenience of an extra set of rails in streets with very heavy traffic, I may use the modification shown in Figs. 5 and 6. In this case I use one magnetic rail M, which is formed so that only parts are exposed on the surface of the roadway. Each length has two flanges *m m'* to support it in the asphalt. The part *n* is the place where the magnetic main makes the contact under the influence of a passing magnet. The magnetic main is shown in this modification as consisting of an iron cable covered with short pieces of tube of similar material, and it rests in a base trough-shaped or semi-circular copper conductor C, which constitutes the "main" proper. The action of the parts is precisely similar to that previously described.

Having now particularly described and ascertained the nature of my said invention and in what manner the same is to be performed, I declare that what I claim is—

1. The means for conveying electricity to tram-cars, consisting of an electric main, a continuous flexible magnetic main, a surface-contact piece or pieces, and a magnet and current-collector situated on the car, substantially as herein described.

2. The combination of magnetic rails consisting of short lengths of rail in two parallel series, such lengths being insulated both electrically and magnetically in a longitudinal

and electrically connected but magnetically insulated in a transverse direction, a continuous flexible magnetic main, and an electric magnet and current-collector situated on the car, substantially as herein described.

3. The combination of magnetic rails, consisting of two parallel series of short lengths of rail, of which one series is exposed above the track and the other covered, and which are electrically and magnetically insulated longitudinally and electrically connected but magnetically insulated transversely, a continuous flexible magnetic main and an electric main in the track, and a magnet and current-collector on the car, substantially as herein set forth.

4. The combination, with a car and a track therefor, of magnetic contact-pieces on the track, and a magnet having rolling pole-pieces on the car, substantially as and for the purpose herein set forth.

5. In electrical-conducting apparatus for tram-cars, contact-pieces, each consisting of two series of short lengths of rail insulated magnetically and electrically in a longitudinal direction, and connected together transversely, so that the lengths of one series will overlap those of the other, as herein described, according to what is herein termed the "hit-and-miss principle."

ALEXANDER LOGIN LINEFF.
